SEALABLE TAG

Filed April 23, 1942

UNITED STATES PATENT OFFICE

2,346,881

SEALABLE TAG

Francis Paul Valenti, Chicago, Ill.

Application April 23, 1942, Serial No. 440,178

5 Claims. (Cl. 292—322)

This invention relates to sealable or lockable checks, or tags combined with sealing means whereby the same may be quickly and easily secured to baggage and other parcels and to any other mountable units to which it is desirable to affix a suitable identification, part of which in some instances may be torn off and carried by the owner or other person in custody of the movable unit to facilitate repossession thereof.

It is well known that in transportation terminals, hotels or other establishments which serve in the custody, handling and carriage of baggage and other parcels, and particularly in the case of baggage carried by porters who are employees of transportation systems, such employees in many instances are compensated on a weekly basis under agreements that the so-called tips received from individual customers shall be paid to the employer. This recently developed system of baggage and parcel serving in which more or less common ordinary forms of baggage checks are employed, has resulted in repeated use of the same baggage check by the porter or other employee conducting such handling with the result that the employer has not received the proper and commensurate compensation paid by the customer.

One of the objects of my invention is to overcome this existing problem by the provision of sealable or lockable checks or "seals" which in some instances may have a tearable "check" portion deliverable to the customer to facilitate subsequent identification of the parcels, and which are so constructed that once affixed and mounted upon the parcel, they cannot be removed without substantially destroying same to render it unusable.

It is a further object of my invention to provide a lockable and sealable tag or check formed of flexible preferably tearable material, which includes a flexible strap portion adapted to be looped about a suitable portion of a parcel, and which has a hook-like anchoring end adapted to lock upon suitable projecting elements within a tunnel-like portion of the unit and so that such anchoring end cannot be manually released without at least partial destruction of the unit.

A further object of my invention is the provision of a lockable tag, check or seal, which may be formed substantially from a single blank of inexpensive material, and which has means thereon for irremovably engaging and locking hook-like anchoring elements upon an end of the strap portion thereof so that upon locked attachment

to a parcel or the like, the unit cannot be manually removed and reused without destruction.

Other and further important objects of my invention will be apparent from the following specification and claims.

This invention, in a preferred form, is illustrated in the accompanying drawing, reference being made thereto in the following description.

On the drawing:

10 Fig. 1 is a perspective view illustrating my lockable and sealable tag or check assembled and mounted upon a typical parcel handle.

Fig. 2 is a top plan view of the blank from which my lockable tag or check is formed as herein described.

15 Fig. 3 is a perspective view with parts broken away and certain parts separated to illustrate the engagement of the locking means.

Fig. 4 is a top plan view with parts broken 20 away and illustrating the "check" end of the unit which bears the locking means and engaging the anchor end.

Fig. 5 is a top plan view with the anchor end 25 of the tag broken away of a slightly modified form of my invention.

Referring to the drawing, reference numeral 10 designates a check or tag of suitable flexible and preferably fibrous material such as cardboard or the like. Said tag 10 may be of any 30 desired shape, preferably of greater length than breadth and preferably substantially elongated, and the outer or free end designated as 10a is defined by a transversely extending line of scoring 11 which extends from one lateral edge to the other of said tag. In the particular illustration of the drawing, to the illustrated shape of which my invention is not limited, an integral part of said tag is relatively narrower and reduced, said intermediate reduced body portion being designated by reference numeral 12.

Numeral 13 designates an elongated integral strap which connects the body portion 12 and connected free end 10a with the opposite anchor end of the sealable tag, and said strap, as well as 45 the remaining parts of the flexible body herein described, are preferably all cut from a single blank which blank is illustrated in Fig. 2 in unfolded and unassembled state. The flexible strap 13 is preferably narrower as illustrated than either the intermediate body portion 12 or the end 10a.

The opposite end of the strap 13 is preferably, though not necessarily, slightly wider and is hereinafter referred to as the anchor end or the free hook-carrying end 14. This forms a continuation 50 of the strap 13. In cutting the blank in the

manufacture of sealable tags or checks of my invention, which is usually by known die-cutting steps, the anchor end 14 is cut with integral oppositely extending wings as illustrated in Fig. 2, said wings or extensions being designated by reference numerals 15 and 15a respectively. Said extensions or wings 15 and 15a are each formed with a recess designated as 16, which is so shaped that hook elements or anchor elements 17 and 17a are thereby formed which open in the direction substantially as illustrated in the drawing.

Scoring lines 18 and 19 are formed substantially along the lines illustrated in Fig. 2 and extend from two points representing the juncture of the lateral edges of the end 14 with the wings or extensions 15 and 15a in a direction converging toward each other to the end edge of the strap. These scoring lines 18 and 19 provide for quick and easy folding over into overlapping positions adjacent each other of the hook elements 17 and 17a for the purposes and functions hereinafter described.

The intermediate body portion 12 is preferably, though not necessarily, provided with a transversely extending slit 20 as illustrated, and also a second transversely extending slit 21. As illustrated in the preferred form of my invention, a panel member 22, which preferably may be of substantially rectangular form and which carries oppositely extending tongues 23 and 24 respectively formed integral with the opposite edges thereof, is adapted to be secured in superposed and overlying position upon the intermediate body portion 12. The securance of said panel 22 may be by any suitable fastening elements and may be exclusively with separate fastening elements such as staples, adhesive or the like, though for the purpose of most economical manufacture I illustrated the said panel 22 and its integral tongues 23 and 24 as being cut from the same blank and forming an extension from the side edge of the intermediate body portion 12.

When the latter method is followed of forming said panel 22, I form a crease or scoring 25 so that said panel 22 may be quickly and easily doubled back and folded over and upon the body portion 12 and secured in such position to form a substantially longitudinally extending tunnel. When integral tabs or tongues such as 23 and 24 are utilized as part of the securing means in the folding over of the panel, the tab 23 is inserted in slit 20 and the tongue 24 is inserted in slit 21, and the remaining free edge secured by suitable fastening element such as the illustrated wire staple 26 which is passed through the overlying opposite edges of panel 22 and the intermediate body portion 12.

In the forming of the panel 22, a substantially V-shaped slit designated as 27 is cut in panel 22 to form an integral anchoring tongue 28 which is disposed in the direction of the main part of the tag 10 when the unit is assembled.

In the positioning or securing of my sealable tag to an article such as baggage or other parcels, usually to the handle thereof, the user will grip the anchor end of my tag or check with its hook members 17 and 17a folded substantially along the scoring lines 18 and 19 into overlapping adjacent positions and insert said anchor end into the opening forming the entrance end of the tunnel between panel 22 and body portion 12, and thereupon push said anchor end, at the same time flexing the strap to the desired degree, to any points wherein the hooks 17 and 17a will be beyond the vortex of tongue 28. The user will then pull backward on the strap or retract the anchor end,

whereupon the hooks designated as 17 and 17a will, by their normal tendency to expand because of being folded into overlying position, engage and hook the tongue 28. In the forms wherein

5 the end tongue 24 is mounted in slit 21, said engaged tongue 24 forms a stop to prevent the user from inserting the hook or anchor end too far, that is partly or wholly through the tunnel. In instances where a fastening element such as a 10 staple is utilized as the member to act as a top for the exit end of said tunnel, such fastening element, i. e. wire staple, will also prevent the anchor end of the strap from being projected through and from the tunnel.

15 An important feature of my invention resides in the locking engagement between the overlapping anchor end, that is the hooks thereof, and the longitudinally directed tongue 28, and further in the accomplishment that the user cannot unhook 20 the anchor end so locked and engaged without destroying the tunnel by tearing it off or by removing the one or more fastening elements which secure the panel 22 to the body portion 12. These accomplishments make practically impossible the 25 unhooking and releasing of the anchor end once it is engaged without destroying or tearing apart the tunnel of the unit, and this thereby prevents the user from reusing the said sealable tag for more than one parcel, and consequently thereby 30 preventing him from collecting a tip or fee from a second or later customer with the same tag.

The herein described securance and the illustrated construction of the tunnel part of the tag is such that in practice the porter or other person using the tag will not be permitted the time 35 by the customer to unfasten relatively secure fastening elements which form the tunnel.

As illustrated in Fig. 5, 22a designates a substantially rectangular panel of cardboard or the like which, in this form, is cut as a separate piece 40 and secured over the intermediate portion 12 of the main body of the tag to thereby form the tunnel in the same manner as has been heretofore described with reference to Figs. 1 to 4, inclusive.

45 Where panel 22 is formed separately as indicated, it may be attached along its lateral edges by suitable fastening elements designated as 26a, as well as by one or more staples 26 in a similar position to that described with reference to Fig. 1.

50 The staple 26a illustrated in Fig. 5 next the tearable tag portion 10a, in this form not only serves as a securing element but also as a stop to prevent projection of the anchor end of the tongue in the assembling operation heretofore described.

55 I am aware that various changes may be made in the embodiment of the invention herein specifically described without departing from or sacrificing any of the advantages of the invention or any features thereof, and nothing herein shall 60 be construed as limitations upon the invention, its concept or structural embodiment as to the whole or any part thereof.

I claim as my invention:

65 1. A sealable means for attaching identification devices to baggage or the like and formed from a single blank of flexible material, an intermediate strap; an anchoring end on one end of said strap having an inwardly folded integral hook adapted, when folded, to normally flex outwardly and; a portion forming a tunnel extending from the opposite end of said strap, said tunnel portion having an angular slit therein forming an integral tongue extending away from said strap; said hook bearing anchor end being insertable through said slit to cause locking en- 70 75

gagement between said anchor end hook and said tongue to prevent removal of said anchoring end.

2. In tearable means for attaching identification units to parcels and the like and formed from a single blank of flexible material; an elongated strap; an anchoring hook-like end integral with said strap having an integral doubled back hook thereon; an integral flat body portion having a pair of transversely extending spaced apart slots therein; an integral panel doubled back upon a portion of said body portion and secured thereto to form a longitudinally extending tunnel, said panel having integral tongues at its opposite ends engaged in said transverse slots; said panel having an angular opening forming an integral tongue extending away from the main part of said strap, said anchor end being insertable in said panel opening and said hook being adapted to engage said tongue to irremovably secure said strap.

3. In an attaching device of the described class and formed from a blank of flexible material and adapted to be irremovably secured to parcels or the like; a flexible strap; an anchor end on one end of said strap having an integrally formed hook thereon; a body portion having a transverse end slit; a panel formed integral with one side of said body portion and secured in position to overlie a part of said body portion, said overlying panel having an angular slit therein forming an integral tongue extending toward the end of said body portion; and a tongue formed integral with said overlying panel and normally

inserted in and engaging said body portion slit, said hook-bearing anchor end being insertable in said panel slit and said hook being adapted to engage said first mentioned tongue to lock said anchor end against removal.

4. In an identification attaching device formed of a flexible and tearable material, an elongated strap having an intermediate connecting portion and an enlarged integral portion at the end of 10 said connecting portion, said connecting portion having secured thereon an overlying panel to form a tunnel between said panel and said intermediate connecting portion; an integral tongue formed by an angular slit in said overlying panel, 15 said tongue extending longitudinally; and hook elements formed integral with the opposite end of said strap and adapted to be inserted into said slit to engage and lock on said tongue.

5. In attaching means for identification devices and adapted to be attached to baggage parcels and the like; a flexible strap; an anchor end integral with said strap including integral folded back wings forming inwardly extending hook elements; an integral transversely slotted strap 25 portion connected to said strap; and a panel secured upon said slotted strap portion; said panel having an angular slit forming an integral tongue extending away from said strap, said anchor end being securable to said tongue by insertion of 30 said anchor end through the slot of said panel and by hooking engagement of said wings on said tongue.

FRANCIS PAUL VALENTI.
